PORTABLE TAPE RECORDER

James K. Hackney, Jr., Mountain View, Calif., assignor to Ampex Corporation, Redwood City, Calif., a corporation of California

Filed Jan. 15, 1962, Ser. No. 68,307

Term of patent 14 years

(Cl. D26—14)

FIG. 1

The back of the recorder is conventionally plain.

I claim:

The ornamental design for a portable tape recorder, substantially as shown and described.
